UNITED STATES PATENT OFFICE.

ANDERS EMIL RYBERG, OF DRAMMEN, AND PEDER CHRISTIAN SCHAANNING, OF CHRISTIANIA, NORWAY.

PROCESS OF BEATING STUFF FOR THE MANUFACTURING OF PAPER IN CONICAL STUFF BEATERS, AS JORDAN ENGINES, MARSHALL ENGINES, ETC.

No Drawing.

Application filed November 4, 1922. Serial No. 598,987.

To all whom it may concern:

Be it known that we, ANDERS EMIL RYBERG and PEDER CHRISTIAN SCHAANNING, subjects of the King of Norway, residing at

5 Drammen and Christiania, respectively, have invented new and useful improvements in the process of beating stuff for the manufacturing of paper in conical stuff beaters (as Jordan engines, Marshall engines, etc.)

10 for which we have filed applications in Germany, Serial R. 55310/55, filed March 7, 1922, patented under No. 375573; Sweden, Serial R. 2446/1922, filed August 21, 1922, pending; Norway, Serial R. 27038/1922, filed

15 August 23, 1922, patented under No. 37526; France, filed August 29, 1922, patented under No. 555491; Belgium, filed August 31, 1922, patented under No. 305114; Finland, Serial 1998, filed Sept. 2, 1922, patented under No.

20 9701; England, Serial 24321/22, filed Sept. 8, 1922, patented under No. 194658; Canada, Serial 271405, filed October 26, 1922, pending), of which the following is a specification.

25 In order to allow of the passage of fibrous substances for the manufacture of paper through the conical beater in the ordinary methods of working, a certain dilution of the paper-stuff with water is indispensable.

30 If the density of the stuff be increased, the speed of passage of the stuff conveyed through the conical beater is diminished, and finally it entirely ceases.

35 In the method of working conical beaters hitherto customary, a great dilution of the stuff with water has been necessary, and in consequence great power is required for

40 beating the stuff, conveying the water and stuff and overcoming the friction of the liquid, in beating. The consumption of power necessitated by the presence of the water is therefore considerable.

45 Now this invention has for its object to feed the fibrous substances to the conical beater with but little water dilution, in order thereby to increase the beating action, whilst at the same time reducing the power consumption or with an equal power consumption to be able to treat a larger quantity of

paper-stuff. For this object the paper-stuff 50 which passes through the conical beater has introduced into it at or before its entrance into the conical beater, a certain quantity of compressed air or gas, and in this way the paper stuff is permeated by the air or gas. 55 This passage of the air or gas through the paper-stuff allows of a denser entrance (greater consistency) of the stuff and assists the beating. The air can be not only introduced before or during admission of 60 the stuff to the conical beater, but also further during the passage of the stuff through the conical beater into the latter itself.

We are aware that it has been proposed 65 by others to introduce steam into the Jordan engine. But the only object of introducing steam has been that the alkalies added to the paper stuff should be maintained hot during the beating process in order to assist 70 the chemical action of the alkalies. As, however, the steam becomes condensated, a very great dilution of the paper stuff with water will be the consequence whereby the expenditure of power for the beater will 75 be uselessly increased. This disadvantage is avoided by the present invention, i. e. by diluting the stuff with very little water only and by introducing compressed air or compressed gas into the stuff either before or at 80 its entrance into the conical beater.

Having now particularly described and ascertained the nature of our said invention and in what manner the same is to be performed, we declare that what we claim 85 is:

In the process for beating paper-stuff the introduction of compressed air into the paper-stuff before or during its admission into the conical beater. 90

In testimony whereof we have signed our names to this specification in the presence of two subscribing witnesses.

ANDERS EMIL RYBERG.

PEDER CHRISTIAN SCHAANNING.

Witnesses:

EDWARD JOHNSON,
DAGNY SYVERSEN.
